CARRYING CASE FOR BOWLING EQUIPMENT AND THE LIKE

Jerome S. Kivett, Kansas City, Mo., assignor to Regal Plastic Company, Kansas City, Mo., a corporation of Missouri

Filed May 23, 1960, Ser. No. 60,699

Term of patent 14 years

(Cl. D87—5)

Fig. 1.

Fig. 2.

Fig. 3.

Fig. 4.

Fig. 1 is a top plan view of a carrying case for bowling equipment and the like, showing my new design.

Fig. 2 is a front elevational view thereof;

Fig. 3 is a side elevational view thereof; and

Fig. 4 is a bottom plan view of a carrying case for bowling equipment and the like.

I claim:

The ornamental design for a carrying case for bowling equipment and the like, as shown.
